UNITED STATES PATENT OFFICE.

HENRY E. LEPPERT, OF NEW BRITAIN, CONNECTICUT, ASSIGNOR TO THE TRUMBULL ELECTRIC MFG. COMPANY, OF PLAINVILLE, CONNECTICUT, A CORPORATION OF CONNECTICUT.

SNAP-SWITCH TERMINAL.

Application filed January 8, 1921. Serial No. 435,810.

To all whom it may concern:

Be it known that I, HENRY E. LEPPERT, a citizen of the United States of America, residing at New Britain, Hartford County, Connecticut, have invented a new and useful Snap-Switch Terminal, of which the following is a specification.

The main object of my invention is to provide a simple, reliable, and inexpensive form 10 of construction which will serve not only as a means for connecting the circuit wire, but also as a switch contact, and in which the parts are so constructed that they may be assembled to constitute either a high or 15 low type of contact.

Briefly stated, the invention consists in providing a post which is adapted to be secured to the switch base and which carries a binding screw, and providing a contact 20 which is reversible and adapted to be secured to the post in either of two positions.

Figure 1 is a side view and partial section of the base of a snap switch showing three terminals embodying my invention, the right 25 and left hand terminals having the contacts in the "high" position, and the other terminal having the contact in the "low" position.

Fig. 2 is a plan and section of the center 30 terminal on the plane of the line 2-2 of Fig. 1.

Fig. 3 is a perspective view showing the two parts of the terminal separately.

Fig. 4 is a vertical projection of a modified construction.

Fig. 5 is a vertical section on the plane of the line 5-5 of Fig. 4.

Fig. 6 is a plan view and section of another form of construction.

40 Snap switches of this type usually have insulating bases such as 6 to which the terminals and operating mechanism are secured.

According to my invention, the terminal 45 consists of two parts, one of which may be termed the post or body portion, and the other of which may be termed the contact portion, and both portions are intended to be stamped or formed from sheet metal. The body portion has a base 7 with one or more screw seats 8, an upright or post 9 carrying a binding screw 10 and lugs or ears 11 on opposite sides of the head of the binding screw. The contact member has a contact

arm 12 which extends at substantially right angles to its base 13. I provide a rivet for securing the base of the contact member to the post of the body member. Preferably this rivet is tubular in form and integral with one of the elements. In this case, the rivet 50 portion 14 is formed integrally from the base of the contact member and is adapted to project through a hole 15 in the post of the body member and to be riveted over as indicated in Figs. 1 and 2. This rivet may 55 be sufficiently strong to hold the parts in a fixed relation, but I prefer to provide projections such as 16 which are located laterally of the rivet 14 and adapted to engage the post 9. In the form shown in Fig. 3, the 60 edges of the post are notched at 17 to receive the projecting lug 16 so as to make a neat flush connection and holds the parts more securely in their proper relation.

From the foregoing, it will be seen that 65 the main body or post member can be formed of one kind of metal and the contact member of another kind of metal, or the contact member may be formed of a metal of different thickness. These advantages result from 70 the formation of the terminal in two parts as distinguished from integrality. The construction also permits the contact member to be assembled on the post member with the contact arm in the "high" or "low" position as shown in Fig. 1. In other words, the contact member is reversible. This makes 75 it possible for the manufacturer to make up the post and contact parts separately in 80 quantities, and then assemble them in either 85 the high or low relation as the case may require. This requires therefore only a single set of simple dies for each part.

In the form shown in Fig. 4, the tubular portion 14' is provided with offsets 16' which 90 fit into offset recesses 17' to prevent the contact member from rotating.

In the form shown in Fig. 5, the contact member has both upper and lower arms 12' so that this member may be termed a double 95 contact member which form of contact is required in some switches of this class.

In the form shown in Fig. 6 the post 9" and the contact base 13" are held together 100 partly by the tubular rivet 14" and partly by the projections 16", which also extend outwardly to form suitable wire-holding lugs at the sides of the head of the binding

screw 10. The shank of the screw in this case passes through the tubular rivet member 14.

I claim:—

5. 1. A snap switch terminal comprising a post member having a supporting base, a contact member having a base secured to said post and having integral projections extending beyond the edges of the post to 10 form wire-holding lugs, and a binding screw supported by one of said members with its head between said lugs.

2. A two-part snap switch terminal, comprising a post member having a base extending substantially at right angles thereto, a separately formed reversible contact member having a contact arm and a base, one of said members having a single rivet formed integrally therewith and passing into the 20 other member and securing said member to the other member, and interlocking means integral with said members for preventing rotation of said members with relation to each other.

3. A snap switch terminal comprising a 25 post member having a central body with two spaced apart supporting feet, a contact member having a contact arm and a base adapted to fit against the body of said post member, one of said members having a centrally 30 arranged opening and the other member having a single rivet integral with it secured in said opening and one of said members having a lug integral with it projecting from one edge and overlapping an adjacent edge 35 of the other member for preventing relative rotation of said members and a binding screw passing through one of said members.

4. A snap switch terminal comprising a post member, a contact member, one of said members having projections extending beyond the edges of the other member to form wire-holding lugs and one of said members having a tubular projection extending through the other member, and a binding 45 screw seated in said tubular projection with its head between said lugs.

HENRY E. LEPPERT.
